SAMPLE BINDER

Chauncey L. Williams, Pelham, N. Y., assignor to
 F. W. Dodge Corporation, New York, N. Y., a
 corporation of New York

Application August 1, 1933, Serial No. 683,205

2 Claims. (Cl. 281—25)

This invention relates to a sample case or binder, and particularly to such a case or binder which will more or less permanently retain relatively flat samples of architectural materials and 5 which may be used in conjunction with a catalogue containing brief descriptions of articles represented by the samples.

One of the most common methods of advertising pursued by manufacturers is the distribution 10 of catalogues which contain descriptions and, where possible, illustrations of the articles or products which the manufacturer produces. Ordinarily each manufacturer gets out his own catalogue and sends it to those whom he believes 15 will be interested in purchasing goods of the type he manufactures. Very frequently such catalogues are immediately discarded by the receivers as they are not then in the market for that particular class of goods; if retained, they 20 frequently become mislaid or lost and are not available when wanted. In either case, the catalogue fails to serve its intended purpose.

Some years ago an organization in this country 25 conceived the idea of having manufacturers turn their catalogues over to it, and it classifying and arranging them in orderly fashion. The idea was put into effect with respect to catalogues of manufacturers of articles and products relating to construction and which are of particular 30 interest to architects. Such a compilation of catalogues, together with one general list of manufacturers and an index of articles and products covering all the various catalogues, bound together in one or more volumes was issued 35 annually and known as "Sweet's Architectural Catalogues". The consolidated catalogues were loaned to all leading architects in the country with the understanding that they would be returned at the end of the year or when called 40 for. Each year the catalogues were either sent in or called in and a new consolidated catalogue was gotten out in which the old catalogues of the individual manufacturers were replaced by new ones.

45 The plan outlined above was found to be not entirely satisfactory in that the catalogues of the various manufacturers were not of uniform size and some were poorly gotten up. In order to overcome that difficulty, the compiler arranged 50 with the manufacturers for it to arrange and publish the catalogues for the various manufacturers. That proved more satisfactory as the individual catalogues were then of uniform size and plan and for several years "Sweet's

Architectural Catalogues" have been gotten out in that form.

From "Sweet's Architectural Catalogues" the architect could readily find any article or product advertised therein, for use in drawing up 60 his specifications for buildings. However, as the catalogues could only give a printed description of the product, or such a description and an illustration of the product where the product was subject to illustration, the architect was still 65 handicapped to the extent that it was impossible for him to see and examine a sample of the product itself. Obviously, from such an examination of a sample of the actual product 70 the architect could get a much better idea of what it was and whether it would best answer the purpose for which it was desired. Furthermore, seeing a sample of the article itself would also suggest to the architect uses to which it 75 might be put in addition to that for which it was specifically designed.

While many architectural materials are of such size and/or nature that it is not practical to distribute samples of them to architects, many 80 products used in the construction of buildings are in flat form and samples of them can be readily and practically distributed. Such flat materials include floor coverings, wall coverings, wall papers, ceilings, insulation sheets, screening, metal lathing, glass, roofing materials, 85 and many other materials of a similar nature.

This invention relates to a case or binder for 90 such flat samples in which the samples are indexed and suitably held in their proper position so that they cannot readily be removed with the attendant danger of them being mislaid or lost, or of being put back in the wrong place. Such 95 a case or binder of samples is adapted to supplement and be used in conjunction with "Sweet's Architectural Catalogues". When a sample case or binder, such as the one forming the subject matter of the present invention, is used to supplement "Sweet's Architectural Catalogues", the general index of the articles and products of the catalogues will indicate by a suitable notation whether or not a sample of the article or product advertised is contained in the case or binder and if it is the proper place at which it can be located. The architect is then enabled to 100 supplement the brief description of the article or product by an examination of a sample thereof, and can thereby determine much more readily whether or not that particular product 105 is satisfactory for its intended use, and also can 110

10 may be folded over upon the part holding the samples 2, as shown in Fig. 2 so that the binder or case may more readily be transported or handled.

5 The inside of the section D is provided with an index 12 to the relatively stiff samples 2 on the left hand side and an index 13 to the more flexible samples 10 on the right hand side. This index includes both the manufacturers' 10 names and the articles or products which are contained in the case or binder. The samples on each side are suitably numbered, as at 14, and arranged in numerical order so that the desired sample may be readily located.

15 The present binder is particularly adapted for use in conjunction with "Sweet's Architectural Catalogues". When so used the index 14^a of the products in the catalogues 15 will have inserted therein the word "Sample" and the number 20 of the sample, as shown at 16, so that the architect in looking in the index for this particular class of products is put on notice that he can find and examine a sample of the product in the sample case or binder. Likewise, if 25 the architect is examining the samples in the case, the index 14 will give him the name of the manufacturer of any particular sample and if he wants a description of the product and/or its price he can locate the description of the article by referring to the manufacturers' index 30 in "Sweet's Architectural Catalogues."

While the sample case or binder herein described is particularly adapted for use in conjunction with a catalogue such as "Sweet's Architectural Catalogues", it is not limited to such use and may be used for binding or retaining samples for any purpose whatever.

I claim:

1. A sample case or binder comprising a back-

40

ing member having at least three sections, a substantially flat fastener-retainer section and cover sections, said cover sections being hinged to the fastener-retainer section, and movable into substantially the same plane therewith, a substantially uniplanar base member secured to the fastener-retainer section of the backing member, said base member having upstanding spaced ears at each end thereof, the ears at each end of the base member having aligned openings, a curved sample-retaining member having arcuate portions at each end lying between the spaced ears, and fastening means passing through the ears and arcuate end portions of the ends of the sample-retaining member for fastening said member to the base member.

2. A sample case or binder comprising a backing member having at least three sections, a substantially flat fastener-retainer section and cover sections, said cover sections being hinged to the fastener-retainer section, and movable into substantially the same plane therewith, a substantially uniplanar base member secured to the fastener-retainer section of the backing member, said base member having upstanding ears at each end thereof, the ears of each end of the base member having aligned openings, a curved flat semi-circular sample-retaining member having arcuate portions at each end, said arcuate portions lying between the spaced ears, and fastening means passing through the ears and arcuate end portions at the ends of the sample-retaining member and permanently secured therein for fastening said member to the base member.
